CEMENT INJECTION GUN FOR USE IN TOTAL JOINT SURGERIES

Ricardo J. Heros, Memphis, Tenn., assignor to Richards
Manufacturing Company, Inc., Memphis, Tenn.

Filed Mar. 29, 1974, Ser. No. 456,274

Term of patent 7 years

Int. Cl. D24—02

U.S. Cl. D83—12 A

FIG. 1

FIG. 2

FIG. 3

FIG. 4

FIG. 1 is a top plan view of the cement injection gun for use in total joint surgeries, showing my new design, the bottom being substantially similar thereto.

FIG. 2 is a side elevational view thereof, the opposite side being substantially similar thereto.

FIG. 3 is an end elevational view thereof.

FIG. 4 is an end elevational view thereof from the opposite end from that shown in FIG. 3.

I claim:

The ornamental design for a cement injection gun for use in total joint surgeries, as shown and described.
